DENTAL STERILIZER

Victor H. Dietz, Ypsilanti, Mich.

Application February 20, 1950, Serial No. 145,237

8 Claims. (Cl. 250—51)

1

My invention relates to the sterilization of dental handpieces and their attached contra-angle and inserted burrs or stones.

It is an object of my invention to provide a dental chair-side technic for substantially suppressing surface contaminants and maintaining the sterility of dental handpieces, their attached contra-angles and inserted burrs.

It is a further object of my invention to provide a sterilizing apparatus which may be positioned adjacent the dentist's chair and into which the dental handpiece with its attached implements may be easily inserted and withdrawn for subjecting them to the germicidal rays of an electric lamp within the apparatus for the destruction of bacteria which may have accumulated on the instruments from use especially in a patient's mouth.

A still further object of my invention is to provide a dental handpiece and attached instrument sterilizing apparatus which includes a cabinet having a sterilizing lamp mounted therein, a relatively large opening within the front of the cabinet through which may be inserted and withdrawn the handpiece, a slotted end joining with a slotted front and the front opening for receiving the handpiece, a holding element for retaining the handpiece within the cabinet so as to be subject to the lamp's rays, a closure for the opening in the cabinet, a closure operator and a reflector within the cabinet for directing rays from the light onto the handpiece and any instruments attached thereto.

A yet still further object of my invention is to provide a sterilizing apparatus as immediately above described that is provided with a movable lamp, a foot pedal operator which is connected with the movable closure or door and the movable lamp so that movement of the foot pedal in one direction moves the closure to expose the front opening and moves the lamp away from the handpiece so that the handpiece may be inserted or withdrawn from the cabinet while movement of the foot pedal in the opposite direction closes the door or closure and moves the lamp toward the inserted handpiece.

A still further object of my invention is to provide a sterilizer apparatus as just described and a locking device whereby the door of the sterilizer may be locked in its open position.

Still further objects and the entire scope of applicability of the present invention will become apparent from the detailed description given hereinafter; it should be understood, however, that the detailed description and specific

2

examples are given by way of illustration only and, while indicating preferred embodiments of the invention, are not given by way of limitation, since various changes and modifications within the spirit and scope of the invention will become apparent to those skilled in the art from this detailed description.

Reference will now be had to the drawings wherein:

- 10 Figure 1 is a front elevation of the sterilizer apparatus showing the foot pedal attachment for operation of the door of the sterilizer;
- 15 Figure 2 is a side view of Figure 1 as seen from the right hand side with a portion of the foot pedal housing broken away;
- 20 Figure 3 shows in enlarged detail the door mounting and pivotal operating means;
- 25 Figure 4 is a cross sectional detailed view along line 4—4 of Figure 1 showing the snap attachment for securing the front wall to the cabinet;
- 30 Figure 5 shows diagrammatically the wiring circuit for the electric sterilizing lamp and its starting means and power supply connection;
- 35 Figure 6 is a left hand end view of the modified form of sterilizer apparatus shown in Figure 7 with a portion of the end wall broken away and the front of the cabinet and door installed;
- 40 Figure 7 is a front view with the front removed of a modified form of sterilizer;
- 45 Figure 8 is a wiring diagram of the circuit for supplying power to the multiple lamps of the sterilizer shown in Figure 7;
- 50 Figure 9 is a front view of the modified form of sterilizer shown in Figure 7 including the front wall in position on the cabinet and the door shown swung in unison with the lamps to an open position;
- 55 Figure 10 is a right hand end view of the sterilizer shown in Figure 9; and
- 40 Figure 11 is a detail enlarged view along lines 11—11 of Figure 9 showing the pivotal mounting for the door and a portion of the door operating linkage.

Throughout the several views like reference characters refer to similar parts.

Much has been done in the way of providing sterilization for the instruments used by the dentist. However, little has been done to provide means for sterilizing the dental handpiece or contra-angle to prevent direct and cross-infection from patient to patient. The dental handpiece or contra-angle is one of the instruments that is used by the dentist the most often and is perhaps cleansed the least. Burrs and mandrels, discs and stones are sterilized thor-

oughly before use. However, the chuck which holds them and which also enters the mouth, may be indifferently cleansed. All too frequently it may be contaminated and may carry contaminations from one patient to another. The dental handpiece and its attachments, as insidious inoculating devices, no doubt constitute an important public health problem. Unsterilized handpieces are dangerous, and their use cannot be condoned. It would appear that the handpiece is the sole surviving source for the transmission of infection in many dental offices.

My invention is therefore directed to a simple chair side procedure for substantially suppressing surface contaminates or maintaining the sterility of handpieces by the use of my specially designed apparatus employing wave emitting electric lamps which provide a sterilizing effect for the handpiece and contra-angle which are placed within the apparatus and exposed to these rays.

Referring to Figure 1, 10 indicates generally a cabinet within which the dental handpiece is placed for sterilization while 11 indicates a foot pedal housing which is positioned below the sterilizer cabinet 10 and is connected therewith by a conduit 12 which carries the operating rod for the door to be described. The cabinet 10 here shown is generally rectangular in shape and is provided with a removable front 13 which may be of a plastic material such as Bakelite, which acts as a barrier for any of the waves emanating from the germicidal lamp 14 mounted in the upper portion of the cabinet 10. The front wall 13 is provided with a relatively large circular opening 15 which permits easy insertion and withdrawal of the handpiece by means of the hand of the operator.

The cabinet 10 is easily installed adjacent the dentist's chair and is attached to the dental machine so that easy access is had for insertion and withdrawal of the handpiece between each operation. In the right hand end wall 16 of the cabinet 10 there is provided a slot 17, see Fig. 2, which extends midway from the center of the end wall to the front of the cabinet. A suitable end plate 18 also slotted in conformity with the slot 17 is attached to the end wall 16 by means of rivets 19. A spring retaining clip 20 is attached as by welding to the end plate 18 which has an inturned flange indicated at 21 in Figure 1. The front panel 13 is slotted as indicated at 22 in Figure 1 so as to closely fit over the projecting portions of the resilient clip 20. This clip 20 is provided with a circular portion 20' which serves as a means for supporting the inserted dental handpiece in a position within the cabinet parallel to the front wall 13 and below the elongated germicidal lamp 14. Mounted within the cabinet 10 is a reflector generally indicated at 23 which provides a radiation chamber within the cabinet for the handpiece. This mirror is of Alzak aluminum and is provided with an anodized surface. The reflector 23 is attached to the cabinet at its upper portion by means of rivets 24 and 25 and is shaped along its bottom portion 26 to conform to the circular opening of the aperture 15 within the front wall of the cabinet. The upper left corner of the reflector 23 extends inwardly and horizontally at 27 and then upwardly vertically at 28 to join the top portion 29 which extends horizontally and parallel to the upper end of the cabinet 10. This offset in the reflector in the upper left hand corner is for the purpose of clearing the operating mechanism which pivotally mounts the door to be described hereinafter. The back wall of

the mirror is best shown at 23' in Figure 2 and extends vertically midway the depth of cabinet 10.

Pivotaly mounted on the outside of the front wall 13 is a door 30 which is circular in shape except for the triangular protuberance indicated at 31 in the upper left hand portion of Figure 1 in which triangular portion 31 the pivotal mounting means best shown in Figure 3 is attached. This door may be of transparent plastic material which not only enhances the appearance of the device but enables the operator to see whether or not the contra-angle is attached and what type of burr or stone was last placed therein when the handpiece is inserted within the cabinet. This door 30 also serves as a barrier for the rays emanating from the germicidal lamp 14 mounted within the cabinet within the confines of the mirror 23.

Referring to Figure 3, a portion of the rear wall of the cabinet 10 is indicated at 32 and has attached to its inner face a bearing 33 within which is supported the rear end of a pivot shaft 34 which extends across the cabinet at the upper left hand corner. Pivot shaft 34 is provided with a square shank 35 at its forward end for receiving the door 30 which is provided with a square aperture as at 36. A screw 37 and a washer 38 are attached to the outer end of the pivot shaft 34 to secure the door 30 in place. Rigidly attached to the pivot shaft 34 is a transversely extending lever 39 having an inturned end 40 apertured at 41 to receive the upper end of the spring 42 which tends to bias the door towards its open position, however, the weight of the door is sufficient to act against the spring 42 to permit the door to close when the foot pedal to be described is released. The lower end of spring 42 is secured to a lug 42' formed on the lower portion of the rear wall of the cabinet, see Figure 2. The other end of lever 39 is apertured to receive a pivot pin 43 which provides a pivotal attachment for a bifurcated end 44 on the upper end of the operating rod 45. Operating rod 45 extends downward through the conduit 12 at the base of the cabinet 10 on into the foot pedal housing 11.

Conduit 12 is attached to the bottom side 72 of the cabinet 10 as indicated generally at 46 by means of nuts 47 and 48 threadedly engaged on the upper threaded end of conduit 12 whereby the cabinet 10 is securely fastened to the conduit 12. The lower end of the conduit 12 at 49 is similarly attached to the foot pedal housing 11.

The foot pedal housing 11 best shown in Figures 1 and 2 is provided with a base portion 50 and a cover portion 51 secured by screws 51' to the base portion. Extending upwardly from the base portion 50 is a lug 52 which is apertured at its upper end to receive a pivot pin 53. A foot pedal 54 is provided with spaced depending lug portions 55—55 intermediate its ends and these are apertured to receive the pivot pin 53 thereby securing the foot pedal in foot pedal housing 11 where it extends outwardly through the aperture 51" in the front wall of the cover 51. The outer end of foot pedal 54 is provided with a tread portion 54' against which the toe of the operator may press and the inner end of the pedal 54 is provided with a depending lug 56 which is apertured to receive the lower right angle bent portion 57 of the operating rod 45. The end of the operating rod as at 57 is secured by means of a cotter pin indicated at 58 which passes through an aperture in the end thereof. Also provided

on the housing 11 is a lock or latch generally indicated at 60 which is in the form of a rod having a vertically extending portion 61 and a right angle portion 62 the latter of which when rotated by means of the attached knob 63 extends the portion 62 underneath the inner end of the foot pedal 54 when same is raised by stepping on the tread 54' whereby the foot pedal is locked in its depressed position to hold the door 30 in full open position. Lock 60 is held in place within the top of housing 11 by means of a washer 63' and a cotter pin as indicated at 64 which passes through an aperture in the upright portion 61 of the latch.

Referring again to Figure 1, the germicidal lamp 14 is mounted in a socket 65 which is riveted to the reflector portion 28 by means of rivets 66.

In Figure 5 there is shown the wiring diagram for supplying power to the lamp 14. A conventional starting switch is indicated at 67 which insets in the circuit a ballast 68 for starting the lamp 14. A conventional snap switch is indicated at 69 for closing the circuit to the lamp 14 from the plug 69 which is connected with a normal 110 volt supply (not shown). Referring to Figure 2, the push button switch 67 is shown mounted in a housing 70 which is attached to the end of the cabinet 10 by means of rivets 71. The on and off switch for the lamp 14 is in the form of a toggle switch 68 which is also attached to the housing 70.

In Figure 4 there is shown a detail of the attachment of the front wall 13 to the cabinet 10. The lower wall of the cabinet is indicated at 72 and is provided at its front end with an upturned flange 73 which is apertured at 74 to receive a resilient fastener 75 anchored at 76 in the removable front wall 13. This arrangement permits the front wall 13 to be easily snapped on and off from the cabinet 10 after the door 30 is removed.

Referring to Figure 7 there is shown in modified form a sterilizing apparatus wherein a movable lamp generally indicated at 80 is provided to swing in unison with the door or closure here shown at 81 and also in Figures 6, 9 and 10. A cabinet is generally indicated at 82 and is of a shape slightly longer than the cabinet 10 shown in Figure 1 of the drawings. Cabinet 82 is provided with a front wall 83 which is attached similar to the front wall 13 in Figure 1 and, therefore, is not shown in detail. Front wall 83 is provided with a relatively large circular opening as indicated at 84 in Figure 9, through which may be inserted the hand of the operator and the dental handpiece 85 as indicated in Figure 7. Front wall 83 is also provided with a slot at 84' which extends from the right hand side of aperture 84 to the right hand edge of wall 83 and there joins with a slot 86 provided in the side wall 87 of the cabinet 82. A slotted cover plate 88 conforming with the slot in the end wall is attached to the end wall 87 by means of rivets 89 and permits the insertion and withdrawal of the handpiece 85 shown in Figure 7. This cover plate 88 is provided with a right angle bent front portion 90 best shown in Figure 7 and serves as a means for attaching as by welding a spring clip device 91 having a circular inner portion 92 within which rests the handpiece 85.

Referring to Figure 11, there is shown in detail the portion of the front wall 83 which is apertured at 93 to receive a pivot shaft 94 having an outer squared end 95 to receive the door 81 which

is securely attached by means of a screw 96 and a washer 97.

Referring to Figure 6, the cabinet 82 has attached to the inner face of its rear wall 82' a boss 100 which supports a pivot shaft 101. A socket base 102 within which the plurality of lamps 80', 80'' and 80''' are mounted is provided with a lug 103 which is apertured at 104 to fit over the pivot shaft 101 shown in Figure 6. Rigidly attached to lug 103 is a second lug 105. The socket is held in place on the pivot shaft 101 by means of a screw 106 threaded into the outer end of shaft 101.

Referring to Figures 6 and 7 there is shown rigidly secured to shaft 94 for operating the door 81 a lever 107 which receives a pivot screw 108 at its outer end and serves to connect the connecting link 109 to the lever 107 in spaced relationship as shown in Figure 6. The lower end of link 109 is pivotally connected to the outer end of lug 105 by means of a pivot screw 110 which passes through a spacer 104', see Figure 6, interposed between lug 104 and lever 109. Thus, the cluster of lamps indicated at 80 and the closure or door 81 operate in unison.

The means for operating door 81 and lamps 80 to rotate same is the pivot lever 111 which is pivoted by a pivot post 112 positioned intermediate its ends and secured to the inner face of outer wall 83. Pivot lever 111 is bifurcated at its right hand end 113, see Figure 7, so as to engage with the pivot screw 108 and extends in between the spaced links 107 and 109 as shown in Figure 6. The left hand end of pivot lever 111 is pivotally connected by a pivot screw 114 to a fitting 115 attached to the upper end 116 of the operating rod 117 which corresponds to the operating rod 45 extending to the foot pedal shown in Figure 1. Operating rod 117 is offset at 116', see Figure 6, so that the conduit 12 may be attached towards the rear of the cabinet 82. It is to be noted that the bifurcated end 113 of the lever 111 slidably engages with the pivot screw 108 and when pedal rod 117 is moved upward lever 111 rotates clockwise so as to move the pivot screw 108 in a counterclockwise arc and thereby rotates link 107 about its pivot 94 and lug 105 about its pivot 101 in a counterclockwise direction so as to rotate the lamp cluster 80 and the door 81 also in a counterclockwise direction. This action permits the door 81 to uncover the front aperture 84 and the lamp cluster 80 to move away from the handpiece 85 with its attached contrangle 85' and inserted burr 85''. This action permits the placement of the hand of the operator within the aperture 84 to grasp the handpiece 85 and remove it from the cabinet 82 where it has been held therein by the clip portion 92 in a position parallel to the plane containing the front panel 83.

In Figure 8 there is shown a circuit diagram including the electric lamps 80', 80'', 80''', connected in parallel to a power supply indicated at 118 through a cut off switch 119 and a starter switch 120 connecting with a ballast 121 for purposes of starting the ignition of the lamps. The cut off switch 119 is shown as a toggle switch mounted on the side wall 87 of the cabinet in Figure 10 and the switch 120 is shown as a push button switch also mounted in a housing adjacent the toggle switch 119 on the end 87 of the cabinet 82.

In the modified form of sterilizer shown in Figures 6-11 the reflector is shown generally at 118. The reflector 118 is mounted in the

cabinet 82 by being attached by rivets 119 passing through the top 120 of the cabinet. Suitable spacers 121 through which the rivets 119 pass space the upper side 122 of the reflector from the inner face of the top 120. The reflector is provided with a rear wall 123, a right hand end wall 124, a bottom wall 125 and a left hand end wall 126. Right hand end wall 124 is slotted at 127 to permit insertion and withdrawal of the handpiece 85, see Figure 7. The left hand end wall 126 is slotted at 128 to permit free swinging movement of the left hand end of lever 111 which extends therethrough.

The ballast 121 is shown in Figure 7 as mounted in the lower right hand lower corner of the cabinet 82 and is connected in circuit as shown in Figure 8 as described heretofore.

In the process of operating the germicidal lamps which may be ultra-violet, mercury arc, or low pressure mercury vapor arc lamps whose rays have germ destroying properties certain rays are also produced which have a wave length which ionizes the atmosphere oxygen to produce ozone. The ozone exerts an oxidizing or "masking effect" upon the oil or grease used in lubricating the handpiece and thereby it is rendered completely non-odorous. By locking the door open and with the lamps ignited the apparatus may be used to deodorize the office.

The opening and closing of the door of the apparatus is of no consequence as to the possibility of bacterial contamination from the air. Air-borne bacteria are quite dry and unprotected, and as such are immediately destroyed upon being wafted into an ultra-violet ray stream.

The dental sterilizer according to my invention is easily installed adjacent the dentist's chair and provides a means of suppressing contamination before and during use of the handpiece and contra-angle on a patient. The apparatus is simple to use in any dental procedure and constitutes not the slightest encumbrance thereto.

I claim as my invention:

1. A sterilizing apparatus for a dental handpiece and contra-angle comprising a cabinet having a relatively large opening in its front wall for insertion and withdrawal of said handpiece and contra-angle, a retaining means for the handpiece in a side wall of the cabinet adjacent said front wall opening adapted to engage and hold the inserted handpiece, a movable closure for said front wall opening, operating means for said movable closure whereby said closure is moved to close the front wall opening and to expose said front wall opening, a germicidal radiation source mounted for movement in said cabinet adjacent said inserted handpiece and contra-angle, means for moving said movably mounted germicidal radiation source connected with said closure operating means whereby actuation of said closure operating means to expose said front wall moves said germicidal radiation source away from said handpiece and attached contra-angle and actuation of said closure operating means to close the front wall opening moves said germicidal radiation source toward and adjacent to the handpiece and contra-angle.

2. A sterilizing apparatus of the character described in claim 1 including a reflector positioned within the cabinet whereby rays from the germicidal radiation source are made to fall on said handpiece and contra-angle.

3. A sterilizing apparatus for a dental handpiece and contra-angle comprising in combination a cabinet having a relatively large opening

in its front wall for insertion and withdrawal of said handpiece and contra-angle, said relatively large opening being connected by a slotted opening in the same front wall with a slotted opening in an adjacent side wall of said cabinet for insertion and withdrawal of the handpiece, a retaining means for the handpiece attached to the cabinet adjacent said side slot opening for retaining the handpiece inside the cabinet substantially parallel to the plane containing the front wall and front wall opening, a movable closure for the front wall opening attached to said cabinet, means connected with said closure for moving it to uncover and cover said front wall opening, a germicidal radiation source disposed in the cabinet whereby rays therefrom may fall on the handpiece and contra-angle, electrical power means for said germicidal radiation source and a switch for turning on and off said power means.

4. A sterilizing apparatus of the character described in claim 3 wherein said closure operating means includes a pivotal mounting for the closure attached to the cabinet, a foot pedal base below the cabinet, a foot pedal pivotally mounted in said base, a rod pivotally connecting the foot pedal and the pivotal mounting for the closure whereby movement of the foot pedal in one direction moves the closure to open position and movement of the foot pedal in the reverse direction allows said closure to move to a closing position.

5. A sterilizing apparatus of the character described in claim 4 including a lock connected with said closure operating means for locking the closure in its open position.

6. A sterilizing apparatus for a dental handpiece and contra-angle comprising a cabinet having a relatively large opening in its front wall for insertion and withdrawal of the handpiece and contra-angle, a slotted end wall adjacent the front wall opening and a slot in the front wall connecting the front wall relatively large opening and said side wall slot for insertion and withdrawal of the handpiece, retaining means for the handpiece attached to the cabinet adjacent the side slot for holding the handpiece in substantial parallel alignment with the plane containing the front wall and front wall opening, a reflector in the cabinet encompassing said inserted handpiece and contra-angle except on its side toward the front wall opening and the area of said end wall slot, a movable closure attached to the cabinet for the cabinet front wall opening, germicidal radiation source mounted for movement within said cabinet adjacent the inserted handpiece and contra-angle, operating means for moving said closure and germicidal radiation source in unison whereby movement of the closure to expose the front wall opening moves the lamp away from the handpiece and contra-angle to permit removal of the handpiece and contra-angle from the cabinet and movement of the closure to close the front wall opening moves the germicidal radiation source toward the handpiece and contra-angle which has been inserted within the cabinet.

7. A sterilizing apparatus of the character described in claim 6 wherein the operating means for the movable closure and movable germicidal radiation source include a pivotal mounting within the cabinet for the closure, a pivotal mounting within the cabinet for the germicidal radiation source, a link pivotally interconnecting said pivotal mountings for the closure and the germicidal radiation source, a foot pedal base positioned below said cabinet, a foot pedal pivotally mounted in the base and pivot means inter-

connecting said foot pedal and said link whereby movement of the foot pedal in one direction pivots the closure to expose the front opening of the cabinet and moves the germicidal radiation source away from the handpiece and contra-angle and movement of the foot pedal in the other direction moves the closure and germicidal radiation source in the opposite direction.

8. A sterilizing apparatus for a dental handpiece and contra-angle comprising a cabinet having an opening in a wall thereof to permit insertion and withdrawal of said dental handpiece and contra-angle, means for supporting said dental handpiece and contra-angle in said cabinet adjacent said opening, a plurality of germicidal producing radiation sources mounted for movement in said cabinet and disposed adjacent said dental handpiece and contra-angle, at least one of said radiation sources being disposed between said dental handpiece and contra-angle and said opening and means for moving said movable mounted radiation sources from said position

wherein said radiation sources are disposed adjacent said dental handpiece and contra-angle with at least one of said radiation sources being interposed between said dental handpiece and contra-angle and said cabinet opening to a location within said cabinet wherein said radiation sources are disposed in a position remote from said dental handpiece and contra-angle from said dental handpiece and contra-angle whereby said dental handpiece and contra-angle may be withdrawn from said cabinet through said opening therein.
